UNITED STATES PATENT OFFICE.

OLIN J. GARLOCK, OF PALMYRA, NEW YORK, ASSIGNOR TO GARLOCK
PACKING COMPANY, OF PALMYRA, NEW YORK.

MACHINE FOR FORMING RING-PACKING.

SPECIFICATION forming part of Letters Patent No. 695,605, dated March 18, 1902.

Application filed June 21, 1901. Serial No. 65,518. (No model.)

To all whom it may concern:

Be it known that I, OLIN J. GARLOCK, of Palmyra, in the county of Wayne and State of New York, have invented a new and useful Improvement in Machines for Forming Ring-Packing, which improvement is fully set forth in the following specification and shown in the accompanying drawings.

My invention is a machine for rapidly and cheaply forming small packing-rings from circular disks of packing material, the same being hereinafter fully described, and more particularly pointed out in the claims.

Referring to the drawings, Figure 1 is a front elevation of the machine with some parts broken away and omitted. Fig. 2 is an end elevation of the machine seen as indicated by arrow 2 in Fig. 1 with some parts omitted. Fig. 3 is a vertical cross-section of the machine, taken on the dotted line 3 3 in Fig. 1, parts being broken away and omitted. Fig. 4 is a plan of the machine with parts broken away, parts being shown in two positions by full and dotted lines. Fig. 5 is a front elevation of the perforated wad-plate detached. Fig. 6 is a vertical cross-section of the machine, taken on the dotted line 6 6 in Fig. 1, further showing the construction, parts being omitted. Fig. 7 is a vertical cross-section on the dotted line 7 7 in Fig. 1, parts being broken away. Fig. 8 is an end view of the machine seen as indicated by arrow 8 in Fig. 1, a part being broken away and the shifting crank shown in two positions by full and dotted lines. Fig. 9 further shows parts of the intermitting mechanism, the crank being shown in two positions by full and dotted lines. Fig. 10 is a face view of the wad-plate and the feeder, the section being as on the dotted line 6 6 in Fig. 1. Fig. 11 is a view of the feeder and associated parts seen as indicated by arrow 11 in Fig. 10, parts being broken away. Fig. 12 is a front elevation of parts at the middle of the machine with parts shown in various positions by full and dotted lines. Fig. 13 is a front elevation of a part of the safety-stop mechanism. Fig. 14 is an end view of the safety-stop barrel seen as indicated by arrow 14 in Fig. 13. Fig. 15 is a longitudinal section of the safety-stop barrel, showing the in-

terior construction. Fig. 16 is a top view of the barrel, parts being broken away and shown in various positions by full and dotted lines, the section being on the horizontal broken dotted line 16 16 in Fig. 17. Fig. 17 is a side elevation of a part of the trip mechanism with parts broken away and the trip-bolt shown in two positions by full and dotted lines, the section being as on the vertical dotted line 17 17 in Fig. 16. Fig. 18 is a front elevation of 60 parts, showing the engagement of the trip-bolt with the trip-bar. Fig. 19 is a front elevation of the wad-discharger and associated parts, the section being as on the vertical dotted line 19 in Fig. 10. Fig. 20 shows the primary wad-backer and associated parts, parts being in horizontal longitudinal section as on the dotted line 20 in Fig. 12. Fig. 21 is a view of the core-displacer with associated parts, parts being in horizontal section as on the dotted line 20 in Fig. 12. Fig. 22 is a plan of the secondary cutter-shaft with associated parts, parts being horizontally sectioned as on the dotted line 22 in Fig. 12. Fig. 23 is a side elevation of the secondary cutter-head with parts 70 broken away, parts being in vertical section as on the dotted line 23 in Fig. 22. Fig. 24 is an end view of the cutter-head seen as indicated by arrow in Fig. 23. Fig. 25 is a side elevation of the upper part of the middle standard of 80 the frame, showing the perforations and some associated parts. Fig. 26 shows the wad before being acted upon by the primary cutter. Fig. 27 shows the same after being cut half through by the primary revolving cutter. Fig. 28 85 shows the completed ring, the center piece having been separated from the annular part and removed. Fig. 29 is a side elevation of a part at the upper end of the middle standard, showing means for disposing of the center 90 pieces and the rings, a part being sectioned as on the dotted line 29 29 in Fig. 31. Fig. 30 is plan of the barrel for the center pieces with some associated parts, parts being in horizontal section as on the dotted line 30 in 95 Fig. 29. Fig. 31 is a section taken on the broken dotted line 31 31 in Fig. 29 further showing the relation of the parts. Fig. 32 is a diametrical section of a part at the center of the wad-plate, taken as on the dotted line 100

32 32 in Fig. 5, further showing the form of the parts and the manner of accurately placing the wad-plate upon the intermitting spindle. Fig. 33 is a rear elevation of the reciprocating 5 cam and associated parts, parts being broken away and other parts shown in various positions by full and dotted lines. Fig. 34 is a horizontal section of parts on the primary cutter-shaft, taken as on the dotted line 34 in 10 Fig. 7, parts being broken away. Figs. 1 to 4 and 6 are drawn to a scale about one-sixth size, Figs. 7 to 9 and 33 to a scale one-fourth size, Figs. 5 and 10 to 12 to a scale one-third size, Figs. 13 to 18, 21 and 22, 29 to 32, and 15 34 to a scale one-half size, Figs. 19 and 20 to a scale three-fourths size, and Figs. 23, 24, 26, 27, and 28 are drawn full size.

Referring to the parts shown, A, Figs. 1 to 20 8, is the frame of the machine, supported upon suitable legs B.

C, D, and E are standards secured to the frame to support the working parts of the device.

F is the driving-shaft of the machine, held 25 by the standards and provided at its overhanging end with a step-pulley G upon which to receive an ordinary driving-belt to actuate the machine.

H is a spindle resting in bearings in the 30 standards C D, provided at its right-hand end with a circular wad-plate or perforated disk I, rigid with the spindle.

K is a notched or recessed intermitting 35 wheel rigid with the overhanging end of the spindle H.

L is a crank for turning the wheel K at intervals, held upon a shaft M, resting in bearings in the standards C D.

N is a pinion on the driving-shaft F engaging 40 a gear O on the shaft M, by means of which the latter is turned to actuate the wheel K and spindle H.

P is a clutch-section rigid with the pinion N and with said pinion adapted to turn freely 45 on the shaft F.

R is a sliding clutch-section held to turn with the shaft F and adapted to engage the section P for driving the machine.

S is a lever for controlling the sliding clutch-section R for starting or stopping the machine 50 while the shaft F continues to rotate.

T (see also Fig. 20) is a primary cutter-shaft, and U (see Figs. 12 and 22 to 24) a secondary cutter-shaft for cutting the center 55 pieces m^2 , Figs. 27 and 30, out of the blank disks or "wads" to form the packing-rings.

The former shaft is rapidly rotated by means of a pinion V thereon, Figs. 1 and 4, engaged by a gear W, rigid with the driving-shaft F, 60 and the shaft U is similarly rotated by means of a pinion X on said shaft, Figs. 1 and 2, engaged by a gear Y, rigid with the driving-shaft. The pinions V and X are not rigid with the respective shafts T and U, but

65 splined thereon, so while turning with the

shafts the latter may each move endwise through its pinion.

Z, Figs. 1, 2, and 12, is a shaft coaxial with the spindle H, normally rigid in the standard E and connected with said spindle, preferably 70 by means of a conical antifriction-bearing a , as shown in Figs. 4, 10, and 32, which serves to keep the two shafts accurately in line.

A', Figs. 3, 4, and 12, is a carrying-head adapted to slide or have longitudinal motion 75 upon the shaft Z.

B', Figs. 1 to 7, is a cam rigid with the shaft M, and C' a vertical link adapted to be moved alternately forward and back by means of a roller b, Fig. 7, held by an extended part 80 n^2 of the link in position to traverse the sinusoidal race in the cam as the latter revolves.

D', Figs. 1, 3, and 7, is a horizontal bar rigid with the link C' and connected at its opposite end with a pair of rocker-arms E', Figs. 85 1, 3, and 4, adapted to turn upon trunnions c, held by a horizontal floor or plate F', joining the standards D E.

At their upper ends the rocker-arms E' engage between lugs d on opposite sides of the 90 carrying-head A', Figs. 1, 3, and 4, by means of which said head is reciprocated by the cam B' along the rigid shaft Z, the bar D' sliding through a bearing in the standard D. At its upper end the link C' is connected with 95 the primary cutter-shaft T by means of a pin e, Figs. 7, 33, and 34, projecting from a ring k^2 on the shaft and piercing the link. By this means the cam as it revolves serves also to reciprocate the shaft T endwise in its 100 bearings in the standards C D. The shaft turns freely within the ring, the latter being held to place on the shaft by means of a loose washer o^2 and collar p^2 , made rigid with the shaft. 105

From the description of the device so far given it will be understood that in the reciprocatory motions of the parts the carrying-head A' on one side of the wad-plate I and the primary cutter-shaft T on the other side 110 of said plate move alternately toward and from the plate and each other as the cam B' revolves. The wad-plate is formed with six equal circular perforations 0 1 2 3 4 5, Figs. 5 and 10, the axes of which are parallel with 115 the axis of the plate. These perforations are equally spaced in a circle concentric with the plate, and within them the blank wads or disks g of packing material are received and the several operations of forming the rings 120 successively performed. The carrying-head A' is coaxial with the wad-plate and formed with circular longitudinal openings, Figs. 2 and 3, opposite and in line with the respective openings 1 to 5 in the wad-plate for holding tools in position to enter said latter openings as the head is moved forward. The middle standard D, Figs. 25 and 29, is likewise 125 perforated for holding horizontal parts and tools opposite and in line with the openings 130

1 to 5 in the wad-plate to coact with the opposing tools in the carrying-head, said five openings in the carrying-head, the wad-plate, and the standard D being in line one with another.

G', Figs. 4, 10, 11, and 12, is an inclined feeder for the device, held adjacent to the front face of the wad-plate I, having a race or channel *f*, down through which the blanks or wads *g* descend, the wads being supplied to the feeder by hand. The feeder is formed at its lower end with an angular part *h* to arrest the downward-moving wads and hold the lower one exactly opposite or in front of the opening 1 of the wad-plate. When in this position, the wad is driven laterally into the opening by a plunger *i*, Figs. 1, 4, and 11 to 17, held in the carrying-head A', when the latter is moved forward, as already described, the 15 wad when driven home resting against a rigid stop or backing *k*, held by the standard D, as shown in Fig. 20. The feeder is held to place by a stand *w*, Figs. 10 and 12, secured to the floor F' of the machine, a clamping-bolt *v* in 20 the stand occupying a vertical slot *x* in the feeder, which permits of vertical adjustments of the latter to accommodate wads of different diameters.

The intermitting wheel K is formed with 30 six equally-spaced radial openings 1, Fig. 8, which are successively entered by the pin *m* of the crank L as the latter is revolved, giving to said wheel intermittent motion. On account of this the wad-plate is turned 35 through exactly one-sixth of a revolution at each action of the crank, causing each opening therein to advance one or to the position occupied by the one ahead of it, the plate resting for a time after each advance motion. 40 A wad is driven into each opening in the plate, as above described, as the latter is turned to bring the openings successively into position, and each wad after being advanced to the position 2, Fig. 10, opposite the primary 45 revolving cutter *n*, is acted upon by said cutter moving from the left by the reciprocating link C', as stated. This cutter forms a circular kerf or incision *r*², Fig. 27, half-way through the wad; the latter being held against 50 displacement from the pressure of the cutter by a spring-actuated block or backer *o*, of wood, Figs. 1, 12, and 20, supported by the carrying-head A' and advanced against the wad by a forward motion of said head. Another 55 shift of the wad-plate brings the opening holding the incised wad to the position 3, where the wad is acted upon by the secondary cutter *p*, Figs. 1, 12, 22 to 24, moving from the right, held in the secondary cutter-shaft U, 60 supported by the carrying-head A'. The cutter *p*, acting on the uncut side of the wad, completes the severing of the center piece *m*², Fig. 27, from the outer part or ring *l*² without, however, displacing the parts. The two 65 cutters *n* and *r* are adjusted to describe circles of equal diameters, so as to form a straight

and true hole through the wad. The next turn of the plate brings the wad to the position 4, Fig. 10, where the center piece *m*² is driven out of the ring *l*² by a spring-controlled punch *r*, Figs. 21, 30, and 31, and when the completed ring reaches the position 5 by another turn of the plate it is pushed out of the latter by a discharger *s*, Figs. 4 and 31, rigid in the carrying-head A', into a spout or conveyer 75 H', Figs. 4, 10, 29, and 31. This conveyer is a hollow inclined body supported from the standard D by a bolt or stud *s*², Figs. 4, 29, and 31, adjacent to the rear face of the wad-plate. The conveyer is formed with an opening *t*² opposite the opening 5 in the wad-plate, through which opening *t*² the ring *l*² is pushed by the discharger *s* into the conveyer, as shown.

The several actions performed upon the wad 85 and the parts thereof while in the openings in the wad-plate are simultaneous, the actions all taking place at each forward motion of the primary cutter-shaft T and the carrying-head A', as above described—that is to say, at each 90 advance motion of these parts a fresh wad is taken into the wad-plate at 1 and a completed ring is pushed out of the plate at 5. The parts of the machine are so timed that these advance motions of the shaft T and the carrying-head 95 occur during the intervals of rest of the wad-plate and the intermitting wheel K, said plate and wheel in their turn moving while the shaft T and the carrying-head are back out of the way. This harmony of action 100 among the parts of the machine results from having all said parts actuated directly or indirectly from a single primary operating-shaft M.

To prevent the carrying-head A' from turning while moving longitudinally upon the shaft 7, it is formed with a downwardly-projecting part *t*, Figs. 1, 3, and 12, adapted to traverse in a longitudinal race between guide-strips *u u* on the floor F'. Also in constructing the machine the wad-plate is pierced by openings *y*, Fig. 5, which pass upon longitudinal pins *z*, Figs. 10 and 32, projecting from the hub *a'* of the intermitting spindle H to accurately determine the relative position of 115 said plate and hub. By these means the operating-tools *i o s*, &c., carried by the carrying-head, are caused to always centrally enter the openings in the wad-plate at each forward motion of the head.

The action of the crank L, held by the shaft M, will be clearly understood by viewing Figs. 8 and 9. As the crank turns the pin *m* will strike into an opening 1 in the wheel K, as appears in Fig. 8, and turning the wheel through 125 a one-sixth revolution the pin will pass out of the opening, as appears by dotted position in Fig. 9, leaving the wheel in position for the pin to enter the next succeeding opening as the crank comes around. By this means 130 the wheel and the wad-plate I are turned intermittently through exactly one-sixth of a

- complete revolution at each action of the crank. It is necessary that the plate I be maintained accurately in position during its periods of rest and while the operations above 5 described are being performed upon the wads. To insure this, the intermitting wheel K needs to be held exactly to place by positive action during its periods of rest. This is effected by forming said wheel with peripheral circum- 10 lar indentations or recesses g^2 between the openings 1 and providing the crank L with a circular projecting disk h^2 to occupy the re- cesses g^2 while the wheel is at rest. The radius of the recesses and of the disk h^2 are sub- 15 stantially equal, so the latter practically fills each recess as it is presented, as shown in Fig. 9, this occurring while the crank-pin m is idling or moving around from one opening 1 to the next in succession. The wheel K and 20 the plate I are thus prevented from shifting until the former is again engaged by the pin of the crank. The disk h^2 is cut away to form a circular notch or indentation i^2 to make way for the adjacent edge of the intermitting 25 wheel while the crank is acting on the wheel, as stated, the radius of the notch i^2 being equal to that of the wheel. The relation of this notch i^2 with the wheel is shown by the dotted position of the crank in Fig. 8.
- 30 The cup u^2 , holding the wooden body o, Figs. 1, 12, and 20, is formed with a lengthened reduced part or rod b' , extending back through a bearing in the standard E, the rod being provided with a spiral spring c' in a 35 hollow barrel d', held rigidly in the carrying-head A' by a set-screw e'. This allows the body o to yield if too hardly pressed, and by means of a screw-nut f', threaded on the rod against the barrel d', the end pressure of the 40 body o against the wad may be regulated.
- The punch r, Figs. 21 and 30, for displacing the center pieces of the rings is also preferably provided with an actuating-spring g' in a barrel h', held rigidly in the carrying-head A' by a set-screw i', having an adjusting threaded nut k' for setting the punch.
- The standard D holds a body l', of wood, Figs. 1 and 12, opposite the secondary cutter-head v', with its free end adjacent to the rear 45 face of the plate I to hold the wad against the thrust of the secondary cutter p.
- The wads, Figs. 10 and 26, are slightly larger in diameter than that of the openings in the plate I and enter the latter snugly, and 50 it sometimes occurs that a wad may enter an opening irregularly or improperly and catch on the side of the opening or otherwise, resulting in bringing an unusual pressure against the primary plunger i, with a liability 55 to overstrain the parts. These accidents are provided against by the following means: The plunger, as shown in Figs. 13 to 17, is held in a hollow barrel m', resting in the carrying-head A', having at its inner end a block 60 or shoe n', adapted to move longitudinally in the barrel. This shoe and the inner end of the plunger are pierced by an axial threaded

rod o', upon which is placed a spiral spring p'. The rear end of the rod is held to move freely through a sleeve r', threaded in the rear end of the barrel, serving to confine the spring between its inner end and the shoe n', a turning of the sleeve one way or the other serving to regulate the tension of the spring. Thus should the plunger at any time encounter a misplaced wad, as stated, it will yield 70 backward against the spring, the parts assuming the positions shown by dotted lines in Fig. 16.

s', Figs. 1, 3, 6, 7, 10, 12, and 18, is a horizontal bar resting upon the floor F' and joined to the lever S, as shown. This bar pierces the standard D and the stand w under the feeder G', having an upturned part or hook t' at its free end. The carrying-head A' is 80 formed with a vertical tubular part u', holding a trip-bolt v', with its lower end adapted to engage the hook t'. The barrel m' is formed with a ledge w', Figs. 12, 16, and 17, and the trip-bolt v' is provided with a horizontal bent 85 finger x', the free end of which normally rests upon the ledge w', as shown, said finger occupying a vertical slot y' in the tubular part u'. A spring z', connected with the finger x', tends to draw the bolt v' downward in position to engage the trip-bar s', as shown by dotted lines in Fig. 12 and in Fig. 17. When the finger x' rests on the ledge w', the trip-bolt is held out of engagement with the bar s'. A longitudinal flat spring a', Figs. 12, 16, and 17, secured to the barrel m', has its thickened free end in position to engage the end of the finger x' and to be engaged by the shoe n' when the plunger i is pressed backward, as above stated. The surfaces of contact between said shoe and the spring a' are inclined, so that when the plunger i is pushed back the spring a' will be pressed outward to the dotted position shown in Fig. 16, serving to disengage the finger x' and allow the bolt 100 v' to engage the trip-bar s', as stated. The pressure against the plunger from the cause stated can occur only when the carrying-head A' is moved forward, in which case the lower end of the trip-bolt is at the left of the hook t' 105 of the bar s', so that when said bolt is allowed to drop, as stated, it will catch the hook t', and the succeeding backward motion of the carrying-head will draw the clutch member R out from engagement with the member P, and so 115 quickly stop the machine.

When a wad enters an opening in the plate I improperly, as stated, it needs to be removed. This is effected by means of a dis- 120 charger b', Figs. 1, 4, and 19, held within the stop k, provided with a spring c' to actuate it. The outer end of the discharger is formed with teeth d', engaged by a vertical toothed stem e', held by an enlarged part f' of the stop k. By turning the stem the end of the 125 discharger will be carried against the mis- placed wad, and so force it out of the plate, this being done while the latter is at rest, the 130 machine being stopped, as stated.

The center pieces m^2 are pushed by the punch r into a cavity w^2 in the end of a cylindrical body or receiver z^2 , Figs. 29, 30, and 31, held by the standard D adjacent to the wad-plate. This cavity opens out at the lower side of the part z^2 , through which the center pieces drop, as indicated by arrow x^2 , into some ordinary conveyer or receptacle. (Not shown.)

10. These packing-rings are required of different external and internal diameters, and to produce the various sizes required a series of wad-plates I are supplied for the machine uniform in make except as to the diameters 15 of the openings 0 to 5, which vary according to the diameters of the primary blank wads previously formed by means not involved in this invention; also, in forming these plates it is sometimes found desirable to flute the 20 openings therein, as shown in Figs. 5 and 6, to hold the blank wads from being turned by the action of the revolving cutters n and p .

What I claim as my invention, and desire to secure by Letters Patent, is—

25. 1. A machine for forming packing-rings, having a plate formed with a series of perforations, and a carrying head or body adapted to carry a series of operating-tools to enter said perforations, and means for giving said head or body reciprocal motions, substantially as and for the purpose specified.

2. A machine for forming packing-rings, having a circular body or plate formed with a series of perforations arranged in a circle, 35 in combination with a carrying-head having perforations arranged in a circle corresponding with the perforations in said plate, and means for turning the latter and for reciprocating the carrying-head, substantially as and 40 for the purpose specified.

3. A machine for forming packing-rings, having a plate formed with a series of circular longitudinal perforations equally spaced and arranged in a circle concentric with the 45 plate, in combination with a carrying-head having a series of longitudinal perforations in a circle coaxial with the perforations in the plate, with means for reciprocating the carrying-head and for giving the plate intermittent circular motion, substantially as shown 50 and described.

4. A machine for forming packing-rings, comprising a perforated plate, and a carrying-head adapted for holding a series of operating-tools on one side of the plate, and a tool-carrying shaft on the other side of the plate, the latter and the carrying-head being coaxial with said tool-carrying shaft, with 55 means for moving the latter and said carrying-head alternately toward and from said plate, substantially as shown and set forth.

5. A machine for forming packing-rings, comprising a perforated plate, and a carrying-head adapted for holding a series of operating-tools on one side of the plate, and a tool-carrying shaft on the other side of the 65 plate, the latter and the carrying-head being

coaxial with said tool-carrying shaft, with means for moving the latter and the carrying-head simultaneously toward and then from the plate, with periods of rest after each backward motion of said parts, substantially as 70 described.

6. A machine for forming packing-rings, comprising a plate, a tool-carrying head and 75 a tool-carrying shaft on opposite sides of the plate, with means for moving said head and shaft simultaneously toward and then from the plate, followed by periods of rest, and means for turning the plate during said 80 periods of rest of the tool-carrying parts, substantially as set forth.

7. A machine for forming packing-rings, comprising a plate adapted to turn upon its axis, and a tool-carrying head adapted to move 85 toward and from the plate, with means for giving said plate and the head intermittent motions, the motions of each occurring during the periods of rest of the other, substantially as and for the purpose specified. 90

8. A machine for forming packing-rings, comprising a circular plate having a series of circular longitudinal perforations equally spaced around a circle concentric with the plate, in combination with a carrying-head for 95 carrying a series of tools, and means for reciprocating the head to cause the tools to enter said perforations at intervals, and for turning the plate intermittently through parts of a revolution equal to the circular distance 100 between the centers of adjacent perforations, substantially as set forth.

9. A machine for forming packing-rings, comprising a rotary shaft, a circular plate on the shaft, and a wheel rigid with the shaft, 105 and means to turn said wheel, in combination with a fixed shaft coaxial with said rotatory shaft, and a carrying-head on the fixed shaft, with means to reciprocate said head, substantially as shown and described. 110

10. A machine for forming packing-rings, comprising a shaft, a plate on the shaft, a wheel rigid with the shaft, the plate having a series of perforations in a circle equally spaced, and means for turning the wheel intermittently through parts of a revolution 115 equal to the distance between adjacent perforations in the plate, substantially as shown and set forth.

11. A machine for forming packing-rings, 120 comprising a shaft, a circular plate on the shaft, a wheel rigid with the shaft, the plate having a series of perforations, and the wheel having indentations equal in number to the perforations in the plate, and means for turning said wheel intermittently through parts of a revolution equal to the distance between two adjacent indentations therein, and a carrying-head adapted to move successively toward and from said plate, and means for reciprocating said carrying-head, substantially 125 as set forth. 130

12. A machine for forming packing-rings, comprising a shaft, a circular plate on the

shaft, a wheel rigid with the shaft, the plate having equally-spaced perforations and the wheel having equally-spaced openings equal in number with the perforations in the plate, 5 and a crank adapted to engage with the openings in the wheel to intermittently turn the latter, and means for turning the crank, substantially as specified.

13. A machine for forming packing-rings, comprising a rotatory shaft, a circular plate on the shaft, and a wheel rigid with the shaft, the plate having a series of perforations equally spaced around a circle concentric with the shaft, and the wheel having equally-spaced peripheral indentations equal in number to the perforations in the plate, and means for turning said wheel intermittently through parts of a revolution equal to the circular distance between adjacent indentations, in combination with a fixed shaft coaxial with said rotatory shaft, and a carrying-head on the fixed shaft, with means to reciprocate it toward and from the plate, said head having perforations or seats for holding a series of tools opposite the perforations in the plate and adapted to enter the latter as the carrying-head is advanced, substantially as specified.

14. A machine for forming packing-rings, comprising a rotatory shaft, a circular plate on the shaft, and a wheel rigid with the shaft, the plate having a series of perforations equally spaced in a circle concentric with the axis of the shaft, and the wheel having equally-spaced peripheral indentations equal in number to the perforations in the plate, a counter-shaft and crank thereon having a pin adapted to engage with the indentations in the wheel to turn the latter, with means to rotate said counter-shaft, and a fixed shaft and carrying-head thereon, and means to reciprocate said carrying-head, substantially as described and shown.

15. A machine of the kind described, comprising a rotatory shaft and circular plate thereon, a wheel rigid with the shaft, and means for turning the wheel, in combination with a fixed shaft coaxial with said rotatory shaft and having a bearing thereon, and a non-rotatory carrying-head on the fixed shaft, with means for giving said carrying-head reciprocal motions, substantially as shown and described.

16. A machine for forming packing-rings, having a rotatory shaft provided with a circular plate and a wheel, a counter-shaft with crank to engage the wheel, a fixed shaft concentric with said rotatory shaft, a carrying-head on the fixed shaft on one side of said plate, a cutter-shaft on the other side of said plate, a cam on the counter-shaft, and means for connecting said cam with said cutter-shaft and the carrying-head and for rotating the counter-shaft, substantially as and for the purpose specified.

17. A machine for forming packing-rings, having a rotatory shaft provided with a circu-

lar plate and a wheel, a counter-shaft with crank to engage the wheel, a fixed shaft concentric with said rotatory shaft, a carrying-head 70 on the fixed shaft at one side of the circular plate, a cutter-shaft on the other side of said plate, a cam on the counter-shaft, a pair of rocker-arms engaging said carrying-head, a link connected with the cutter-shaft and actuated by said cam, and a connecting-bar for the link and said rocker-arms, with means to rotate said counter-shaft, whereby the cutter-shaft and the carrying-head are caused to move simultaneously alternately toward and 80 from the circular plate, substantially as shown and described.

18. A machine of the kind described, having a driving-shaft provided with engaging clutch members one being shiftable, a fixed shaft parallel with the driving-shaft, a carrying-head on the fixed shaft, with means for reciprocating the carrying-head, a trip-bolt held by the carrying-head, a lever for actuating the shiftable clutch member, a bar connected with 85 said lever, and adapted to be engaged by the trip-bolt, and means for actuating the latter, substantially as and for the purpose specified.

19. A machine of the kind described, having a driving-shaft provided with a rigid clutch, 95 and a movable clutch to engage the rigid clutch, a carrying-head with means to reciprocate it, a trip-bolt held by the carrying-head, mechanism connecting the trip-bolt and the said movable clutch, a barrel held by the carrying-head parallel with the driving-shaft, a spring-pressed axial shaft in said barrel, a spring held by the barrel to engage said trip-bolt, and to be engaged by said axial shaft, substantially as and for the purpose specified. 105

20. A machine of the kind described, comprising a circular plate, a carrying-head having a cutter-holder on one side of said plate, and a longitudinally-movable cutter-carrying shaft on the other side of the plate, with means 110 for reciprocating said carrying-head and the cutter-carrying shaft simultaneously toward and from said plate in lines parallel with the axis of the latter, and for rotating said cutter-holders, substantially as and for the purpose specified.

21. A machine of the kind described, having a circular plate formed with equally-spaced perforations in a circle, a carrying-head having a rotatory cutter-holder on one side of said 115 plate coaxial with a perforation in the plate and adapted to move longitudinally toward or from said perforation, and a rotatory shaft carrying a cutter on the other side of the plate, coaxial with a perforation in the plate 125 and adapted to move toward or from the perforation, with means for reciprocating the carrying-head and said cutter-carrying shaft to cause the cutters to enter said opposing perforations at intervals, and for rotating said 130 cutter-holders, substantially as shown and described.

22. A machine of the kind described, having a perforated rotatory plate, a rigid body on

one side of the plate formed with a cavity opposite and coacting with said perforation in the plate, and a reciprocating part or shaft on the other side of the plate adapted to enter said perforation in the plate, with means for operating said reciprocating part, substantially as shown and described.

In witness whereof I have hereunto set my hand, this 28th day of May, 1901, in the presence of two subscribing witnesses.

OLIN J. GARLOCK.
